UNITED STATES PATENT OFFICE.

WILLIAM N. BOOTH, OF DETROIT, MICHIGAN.

MACHINE FOR ASSEMBLING SPOKED WHEELS.

1,295,683.

Specification of Letters Patent. Patented Feb. 25, 1919.

Application filed April 15, 1918. Serial No. 228,686.

To all whom it may concern:

Be it known that I, WILLIAM N. BOOTH, a citizen of the United States of America, residing at Detroit, in the county of Wayne 5 and State of Michigan, have invented certain new and useful Improvements in Machines for Assembling Spoked Wheels, of which the following is a specification, reference being had therein to the accompanying drawings.

The invention relates to the manufacture of wheels comprising a series of wooden spokes and wooden felly sections which are pressed into engagement with a metallic rim. 15 It is the object of the present invention to obtain a machine in which the work of assembly is expeditiously and accurately performed and which has various features of advantage as hereinafter set forth.

In the drawings:

Figure 1 is a central section through the machine partly in elevation;

Fig. 2 is a side elevation thereof;

Fig. 3 is a sectional plan view; and

25 Figs. 4, 5, 6 and 7 are diagrams showing the several steps in the operation of the machine.

A is the frame of a mechanical press, B is the bed or table therefor, C is a reciprocatory plunger, D a cross head for carrying the plunger, E pitman rods on opposite sides of the machine for actuating the cross head, F cranks for actuating the pitman rods and G the crank-shaft,—all of any suitable construction. Upon the bed B is mounted a frame member H centrally recessed to receive the wheel to be assembled and provided with a series of radial guides H' for clamping jaw members I. The latter are 30 preferably positioned to aline with the spokes of the wheel to be assembled and have their inner ends arc-shaped to engage the periphery of the felly. The members I are simultaneously actuated in a radial direction 35 by an intermittently operating mechanism, which as shown comprises a master gear-wheel J arranged below the bed, a series of pinions K in mesh therewith and a series of shafts L on which said pinions are mounted, 40 passing upward through bearings L' in the member H and provided at their upper ends with a cam or eccentric L² engaging a transversely-slidable bearing block M in the jaw member I. The arrangement is such that 45 whenever the gear-wheel J is in rotation the pinions K will be simultaneously and corre-

spondingly revolved, effecting a revolution of the shafts L, which in turn, actuating through the medium of the transversely-slidable blocks M will actuate the jaw members I radially.

It is essential to the operation of the machine that the jaw members I, after being moved radially inward to clamp the felly and spokes, should dwell in this position 50 during the operation of pressing the felly into the rim. This result is accomplished by providing an intermittently operating mechanism for the gear-wheel J, so timed as to impart to each of the pinions a one-half revolution and carry the cam or eccentric from its outer to its inner limit of thrust. I preferably employ a well-known Geneva movement for intermittently actuating the gear-wheel J, and, as shown, N is a 55 star-wheel rotating with the gear-wheel J, having radial slots N' therein and concave bearings N² in its periphery intermediate said slots. O are cranks mounted on vertical shafts O' journaled in bearings on opposite sides of the frame, said shafts being actuated through the medium of bevel gear-wheels P P' from the main shaft G. The cranks O are provided with roller crank-pins O² for fitting within the radial slots N' 60 and are further provided with locking segments O³ for engaging the peripheral notches N² of the star-wheel. In the operation of this mechanism the continuous rotation of the cranks O will cause the roller crank-pins O² to engage the radial slots N' 65 and actuate the star-wheel N through a segment equal to the throw of the crank. As the roller O² leaves its engagement from the slot N', the segment O³ interlocks with the concave bearing N², thereby holding the star-wheel stationary while the crank is passing through one-half a revolution and into engagement with the next succeeding slot N'. Thus during the continuous rotation of the crank the star-wheel is moving 70 substantially one-half the time and is stationary the other half.

Arranged centrally within the recess in the frame member H is a work-supporting table or platen Q. This is provided with a shank Q' vertically, slidably mounted in a bearing in the bed B and connected by a rod R having a slotted yoke R' embracing the shaft G to a piston R² in a pneumatic cylinder R³. A similar pneumatic cylinder S is mounted upon the cross-head D, the piston

- S' being connected to a rod S² which passes centrally through the plunger C. At the lower end of the rod S² is a flat bearing head S³ with a central downwardly-projecting pin S⁴ engageable with an aperture Q² in the platen Q. The parts are so arranged that the pressure upon the pistons S' and R is in opposite directions so that the work will be clamped between the plate S³ and platen Q, but the pressure in the cylinder R², which is of greater diameter, will be in excess of that in the cylinder S, so that the parts will normally be held with the platen Q in its raised position.
- 15 The plunger C has mounted thereon a head C' with a depending annular flange C² for bearing upon the felly of the wheel. Thus, whenever the cross head D is lowered by the operation of the cranks F and pitman rods E, the head C' and flange C² will press the wheel downward against the resistance of the platen Q and the pneumatic pressure in the cylinder R². In the complete operation of the machine the parts are initially in
- 20 the position shown in Fig. 1, where the platen Q is at the upper limit of its movement. The operator first places the metallic wheel rim in the recess in the member H, where it will engage the guide bearings H² for holding it concentric with the axis of the plunger. The wheel sections are then placed upon the platen Q, these preferably comprising two semi-circular felly sections with radial spokes in engagement therewith, and the
- 25 position of the work supported on the platen is such as to bring the felly sections in the plane of the clamping jaws I. Pneumatic pressure is then supplied to the cylinder S so as to move the rod S² downward carrying
- 30 the head S³ into contact with the upper face of the inner end portions of the spokes, while the pin S⁴, which is slightly tapered, will be forced into engagement with the ends of the spokes. The operating mechanism for
- 35 the press is then tripped, which will start the shaft G in rotation. During the initial movement of this shaft the cranks O, which are driven through the medium of the bevel gear-wheels P P' and shafts O', will actuate
- 40 the star-wheel N, thereby rotating the gear-wheel J and all of the pinions K in mesh therewith. This movement will continue until the eccentrics L², in coöperation with the transversely sliding blocks M, will move the
- 45 jaws I radially inward to the inner limit of their movement. The jaws will thus be brought in contact with the periphery of the felly sections, and in the further movement will press these sections radially inward
- 50 against the resistance of the spokes and the pin S⁴ at the inner end thereof. At the completion of the inward movement the cranks O and roller pins O² are in a position to disengage from the star-wheel, while the locking segments O³ will engage with notches N²,

locking said star-wheel from movement in any direction. During all of the movements thus far described the cranks F are rotating and through the medium of the pitman rods E are actuating the cross-heads D and plunger C in a downward direction. Sufficient clearance is provided between the flange C² of the head C' and the work, so that all of the movements thus far described can take place before the flange C² comes in contact with the felly of the wheel. When, however this occurs, the further downward movement of the plunger will press the felly sections out of engagement with the jaws I and into engagement with the metallic rim which is in registration therewith. Thus without releasing the radial clamping pressure the felly sections are forced into engagement with the rim.

It is very essential to hold the spokes in their proper plane during the movements above described so as to prevent forming an improperly dished wheel. This is effected by the opposed pressures of the pneumatic cylinders R² and S, which press the head S³ and platen Q against opposite sides of the spokes with sufficient force to hold them straight. During the downward movement of the plunger C the cylinder S is carried downward therewith, but this will not disturb the clamp, for the piston S' is free to travel in the cylinder and the pneumatic pressure against the piston R being in excess of that against the piston S', the position of the platen is undisturbed. When the flange C² comes in contact with the felly the downward mechanical pressure is sufficient to overcome the pneumatic pressure in the cylinder R², so that the platen will be forced downward, the same pneumatic clamping pressure on opposite sides of the spokes being maintained. At the completion of the downward movement and when the felly is fully engaged with the metallic rim, pneumatic pressure in the cylinder R² is exhausted, this being accomplished automatically or by the manual operation of a relief valve. As a consequence when the plunger C and head C' are elevated the platen Q will remain in its lowered position, but may be raised to disengage the completed wheel by the re-admission of air into the cylinder R².

What I claim as my invention is:

1. A machine for assembling wheels comprising means for clamping complementary spoked felly sections in a common plane, means for radially compressing said felly sections while clamped in said plane, and means operating subsequent to the radial compression for pressing said felly sections laterally into a rim.

2. A machine for assembling wheels comprising means for clamping complementary spoked felly sections in a common plane and around a central abutment, means for

compressing said felly sections radially opposite the spokes and against said central abutment, and means for laterally pressing said felly sections out of engagement with said radial compression means into engagement with a rim.

3. A machine for assembling wheels comprising means for clamping complementary spoked felly sections in a common plane around a central abutment, a series of radially movable segmental jaws for embracing said felly sections in registration with the spokes thereof, means for actuating said jaws to compress said felly sections and spokes against said central abutment, and means for laterally moving said felly sections and clamping means out of engagement with said segmental jaws and into a rim.

20 4. A machine for assembling wheels comprising a platen for supporting complementary spoked felly sections, a coöperating clamping plate for holding said spoked felly sections in a common plane, a circular series 25 of segmental jaws for embracing said felly sections in registration with the spokes thereof when clamped on said platen, means for moving said jaws radially inward to compress the felly sections and spokes, 30 means for supporting a rim for the wheel in concentric registration with said series of radial jaws, and means for pressing said felly sections and clamping means out of engagement with said jaws and into engagement with said rim.

5. A machine for assembling wheels comprising means for clamping complementary spoked felly sections in a common plane, a circular series of segmental clamping jaws 40 in the plane of said clamping means, means for moving said clamping jaws radially inward to compress said felly sections, and means for pressing the compressed felly sections and clamping means therefor laterally out of engagement with said segmental jaws and into engagement with a rim.

6. A machine for assembling wheels comprising a bed or table recessed to receive a wheel rim, a circular series of segmental jaws 50 radially movable on said bed or table in a plane above said recess, a platen yieldably positioned to support complementary spoked felly sections in the plane of said jaws above said rim, a coöperating clamping plate, means for pressing said clamping plate against the spoked felly sections with a force insufficient to move said yieldable platen, and means for engaging said felly sections and clamping plate to force the same laterally against the resistance of said platen to force the felly sections out of engagement with said jaws and into engagement with said rim.

7. In a machine for assembling wheels, 65 the combination with a circular series of

radially movable jaws and means for actuating the same, of pneumatic means for clamping complementary spoked felly sections in the plane of said jaws and holding the same during radial compression movement, a seat for a rim concentric with said jaws, and mechanical means for pressing said felly sections and pneumatic clamping means therefor out of engagement with said jaws and into engagement with said rim.

8. In a machine for assembling wheels the combination with a platen for supporting complementary spoked felly sections, of pneumatic means for yieldably holding said platen in a predetermined plane, a coöperating clamping plate, pneumatic means for pressing said clamping plate against the spoked felly sections with a force insufficient to overcome the supporting force for said platen, means for radially compressing said felly sections while clamped by said pneumatic means, and means for pressing the clamped felly sections against the supporting pressure for said platen out of engagement with said radial compression means and into engagement with a rim.

9. A machine for assembling wheels comprising a platen for supporting complementary spoked felly sections, pneumatic means for yieldably supporting said platen in a predetermined plane, a seat for a wheel rim below the plane of said platen, means for pneumatically clamping said spoked felly sections upon said platen with a force insufficient to depress the platen, means for radially compressing said clamped spoked felly sections, means for laterally moving said clamped felly sections against the supporting pressure of said platen out of engagement with said radial compression means and into engagement with said rim, and means for relieving the pneumatic pressure before the release of said lateral pressure.

10. A machine for assembling wheels comprising a platen for supporting complementary spoked felly sections, a plate for engaging the central portions of said spokes and clamping the same against said platen, means for applying radial outward pressure to the inner ends of said spokes while clamped on said platen, means for applying radial inward pressure upon said felly sections against the outward pressure on said spokes, and means for forcing said felly sections and clamping means laterally out of engagement with the radial inward compressing means and into engagement with a rim.

11. The combination with an intermittently reciprocated press, of means for yieldably supporting complementary spoked felly sections in the path of said reciprocating press, and intermittently operated radial compressing means timed to operate alter-

nately with the reciprocation of said press whereby said complementary sections are first radially contracted and then forced laterally into engagement with the rim.

- 5 12. The combination with a bed, of a circular series of segmental jaws radially movable on said bed, intermittently operated means for simultaneously actuating said jaws inward and outward, a plunger movable axially of said series of jaws, means for reciprocating said plunger alternately with the intermittent movement of said jaws, a platen for supporting complementary spoked felly sections in the plane of said
- 10 15 jaws, coöperating clamping means for said sections on said platen, and a member actuated by said reciprocating plunger for engaging said felly sections, clamping means and platen and forcing the same laterally out
- 20 25 30 of engagement with said radial jaws and into engagement with a rim.

13. The combination with alternately operating radial compression means and vertical reciprocating means, of a platen for supporting complementary spoked felly sections in the plane of said radial compression means, pneumatic means for supporting said platen, a pneumatically operated clamping plate for clamping said sections against said platen with a force insufficient to overcome the pneumatic support for said platen, and

means actuated by said reciprocating means subsequent to the operation of said radial compression means for forcing the compressed felly sections against the resistance 35 of said platen into engagement with the rim.

14. The combination with means for radially compressing complementary spoked felly sections, of a platen for supporting the felly sections in the plane of said radial 40 compression means, a pneumatic support for said platen, pneumatic clamping means for said sections upon said platen having insufficient pressure to depress said platen, and mechanically operated means for forcing the compressed felly sections out of engagement with said radial compression means and against the resistance of said platen into engagement with a rim. 45

15. The combination with means for holding complementary spoked felly sections in the same plane, of a central pin or abutment for the inner ends of the spokes, means for radially compressing the felly sections and spokes against the resistance of said 50 abutment, and means for forcing the compressed felly sections out of engagement with said radial compression means into engagement with the rim. 55

In testimony whereof I affix my signature. 60

WILLIAM N. BOOTH.
